UNITED STATES PATENT OFFICE

BENJAMIN L. GATES, OF CHICAGO, ILLINOIS

MULTIDISK PHONOGRAPH-RECORD SELECTOR AND PLACER

Application filed April 13, 1929. Serial No. 354,842.

The invention generally relates to phonographs of the type embodying a turntable and instrumentalities for reproducing sounds recorded on a disk or tablet record 5 rotated by and on the turntable, and the said invention resides in the provision of a novel mechanically actuated means to impound a plurality of selected records, and when desired, to select a particular record 10 of the plurality, discharge it from among the plurality and position it upon the turntable to be played in the usual manner.

Another object of the invention is to provide in the novel mechanism referred to, 15 means by which the record may be positioned upon the turntable with a selected side uppermost in order to play a selected one of the two recordings usually provided on records of the disk type.

20 In its more detailed nature the invention resides in the provision of a vertically disposed magazine in which a plurality of record tablets are impounded standing on edge, a record carrier and positioner, the magazine and the carrier being mounted for relative movement to cause a selected magazine compartment to register with the carrier, means to discharge a record from the selected compartment into the carrier, and 25 means to move the carrier to deposit the selected record onto the turntable, the carrier moving means being reversely operable to restore the carrier to its original position, and means also being provided to restore 30 the played record to the compartment from which it was discharged.

Another object of the invention is to provide a novel means to relatively move the record magazine and the carrier into selected associated relations.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended

claims, reference being had to the accompanying drawings, in which:—

Figure 1 is a plan view illustrating the invention, a record being shown in playing position.

55

Figure 2 is a side view, parts being in section and the record carrying arms being shown in the receiving or normal position.

60

Figure 3 is a vertical section taken on the line 3—3 on Figure 2.

Figure 4 is an enlarged detail section taken on the line 4—4 on Figure 2.

Figure 5 is a detail section taken on the line 5—5 on Figure 4.

65

Figure 6 is a detail view illustrating the record carrier operating equipment.

Figure 7 is a horizontal section taken on the line 7—7 on Figure 6.

70

Figure 8 is a detail view illustrating the cam means for operating the record discharging arm.

Figure 9 is a detail view illustrating the cam and detent mechanism for locking the swing arm in selected positions.

75

Figure 10 is a detail view of the record discharge arm operating cam.

80

In the drawings in which like numerals of reference indicate like parts in all of the figures, 1 generally designates the phonograph housing or casing which may be of any suitable design and construction. The head or top board usually provided in such housing is indicated at 2. The turntable operating motor 3 is suspended on its carrying frame 4, the turntable 5 of the machine being rotatable in a horizontal plane above the board 2 in the usual manner.

85

In the practical development of the invention I provide a multi-pocket record magazine 6 which is stationarily supported as at 7 on the head board and casing and is formed of a plurality of registering upper and lower pocket-forming guideways 8 and 9.

90

The pockets, each of which is formed by an upper and lower registering pair of guideways 8 and 9, are spaced apart and all converge to intersect the vertical axis on which the turntable rotates. The purpose for this convergence will be apparent as the description proceeds.

95

100

The records adaptable for use in connection with the machine are of the conventional double-face tablet type and designated by the numeral 10 in the drawings. Light tension keeper springs 11 are mounted in the advance ends of the lower pocket guideways and serve to hold the records in the pockets against tendency to roll forwardly out of the said pockets.

10 The bracket hanger 12 depends from the motor frame 4 and provides a fulcrum mounting as at 13 for a horizontally swingable arm 14 which carries a vertically disposed supporting standard 15 at its rear 15 end. A shaft 16 is mounted on the arm 14 and is rotatable about a horizontal axis in bearings 17 carried by that arm. The shaft 16 projects beyond the front end of the arm and is equipped with a turning handle 18 20 which carries an indicator finger 19, serving a purpose that will be described later.

The shaft 16 is also extended at its rear end where it is equipped with a rack shifter cam 20 and also a carrier lowering and 25 lifting crank 21. The shaft 16 is also equipped, adjacent its front end, with a selected position locking cam 23 and a record discharge arm operating cam 24.

A lock sector 25, having notches corresponding in position to the individual pockets of the magazine 6, is secured to the casing or other suitable support and a spring 30 retracted lock detent 26 is adapted to be forced into a selected one of the sector 35 notches each time the position locking cam 23 is rotated. For this purpose the cam 23 is provided with a notch 27 into which the detent 26 recedes normally and from 40 which the detent is forced into engagement with the selected sector notch as the cam 23 is rotated.

A record pusher or discharge arm 28 is fulcrumed as at 29 on the arm 14 and is provided with a suitably curved offset head 45 30 for suitably engaging the selected record to force it out of the magazine in a manner that will be described later. The offset head operates in the selected record pocket proper while the main body portion of the arm 28 50 operates in one of the spaces between the selected pocket and the next adjacent pocket. It will also be observed that all of the upper pocket-forming guideways 8 are secured as a unit while the lower guides 9 are spaced 55 apart through their whole length excepting their extreme front ends, which are rigidly mounted on the cross bolster 31. This mounting of the lower guideway renders possible the movement of the record 60 discharge arm just above described.

The discharge arm 28 is provided with a short crank finger extension 32, which extends beyond the fulcrum of the arm and rests in a cam groove 33 formed in the cam 35 24. The groove 33 is provided with a dwell

34 a distance in each direction from the normal center and a quick-acting cam portion 35 at the same point at each side of the center and a suitable dwell beyond the quick-acting points and merging at the other or lower center of the cam. In this manner the first movement of the cam in either direction of rotation is without effect upon the discharge arm. At a specified point in the rotation in either direction the quick-acting 75 portion 35 comes into function to move the discharge arm, after which the respective dwell portion 36 will serve to hold the arm in its projected position until retractive 80 rotation restores the cam and arm to the normal position. The cam is thus formed for effecting the same operations in either direction or rotation of the shaft 16.

When the selected record is forced out of its pocket it passes, in its vertical position, between upper and lower grooved arms 37 which serve as carriers to thus receive the record and later change its position from the vertical to the horizontal and deposit it upon the turntable to be played. The arms 90 are fulcrumed as at 38 on an extension of the shaft 39 which is rotatable in a slide block 40 vertically slidable in guide grooves 41 provided in the swingable arm standard 15. 95

Each of the arms 37 includes a lug 42, the said lugs being opposed to one another and there being a spring 43 interposed between each lug and the adjacent portion of the shaft extension 39 which normally tend to 100 force the arms toward each other and into gripping relation with the record.

An adjustable stop screw 44 is mounted, as at 45, on the standard 15 in position to engage the upper one of the arm lugs 42 105 to relieve the upper arm of the tension of its spring so that it will not frictionally engage the record as it is moved between the arms 37 by the discharge arm 28. Each time the carrier is lowered this engagement 110 with the stop screw will be released and the arms 37 will grip the record to secure it against inadvertent displacement.

It will be understood that the grooves in the arms 37 may be made deep enough to 115 enable them to take large or small records 10.

An operating arm 46 projects laterally from the slide block 40 and a gear 47 is mounted upon the rear end of the carrier shaft 39, the end of the shaft adjacent the gear and positioned in the standard slot-way being provided with pins 48 arranged at 90° angle positions and adapted to enter either the upper notch 49 provided in the upper wall of the slideway or the lower 120 notch 50 provided in the lower wall of the slideway, depending on the position of the carrier, either raised or lowered. Thus one of the pin and notch associations will secure the parts against inadvertent movement at 125 130

either the upper normal or lower active positions of the carrier.

The operating arm 46 is link-connected as at 51 with the crank 21 mounted on the rear 5 end of the shaft 16, the said link having a lost motion slot connection with the crank to permit a degree of rotation of the shaft 16 before the crank becomes active to lower the carrier.

10 A pair of alternately active racks 54 and 55 are provided and are carried by a slide bar 56 which is horizontally slideable at 57 on the rear face of the standard 15. A shift lever 58 is connected at one end as at 59 to 15 the shaft bar 56 and is fulcrumed intermediately of its ends to the standard 15 as at 60 and provided at its lower end with a camway 61 to be acted on by the cam 20 secured to the shaft 16. Thus one or the 20 other of the racks will be moved into position for engaging the gear 47 as the carrier is lowered to rotate the shaft 39 a quarter turn in either direction depending on which one of the racks has been shifted. In this 25 connection the handle indicator or pointer 19 comes into function and indicates the direction in which the shaft 16 is rotated. If the shaft is rotated in one direction one of the racks will be brought into position and 30 if rotated in the opposite direction the other of the racks will be brought into position. In this manner the record may be turned with a selected one of its sides uppermost so that a selected one of the face recordings 35 may be reproduced.

A pair of quick-acting release lugs or cams 62 project from the standard 15 into position for engaging the outside faces of the carrier arms 37 as the carrier is moved 40 downwardly. This engagement of the cams 62 forces the arm lugs 42 together and serves to spread the arms 37 and release the record as it reaches the turntable 5. The grooves in the arms 37 are wide enough, and the 45 cams 62 act quickly enough, to retain the record under the carrying influence of the arms as the carrier moves upwardly to its normal position.

If desired, the arms may be rigidly 50 mounted and spaced far enough apart relatively to the turntable to permit rotation of the records in the arms and thus enable playing of the record without any spreading of the arms being necessary.

55 The usual tone arm employed in machines of this kind is generally indicated at 63 and the head board 2 may be cut away as at 64 to permit the necessary swinging of the standard 15.

60 In order to provide for removal of the record from the carrier arms 37 and replacement thereof into the magazine pocket from which it has been removed, I provide a record return arm 65 which is secured 65 upon the upper end of a rock shaft 66 rock-

able about a vertical axis in bearings 67 carried by a bracket extension 68 from the swinging arm 14.

A bevel sector 69 is secured on the lower end of the shaft 66 and is engaged by a gear sector 70 secured on the horizontal rock shaft 71, rockable in bearings 72 on the bracket extension 68 and adapted to be rocked by a cam arm 73 secured on the other end of the said shaft and which is 75 spring-held as at 74 to effect the retracted position of the return arm 65.

The arm 73 is equipped at its free end with a cam head 75 adapted to be engaged, when the return arm 65 is to be actuated, 80 by an actuator finger 76 working in a slot 77 provided in the shaft 16, the said shaft 16 being hollow, and carried by a push rod 78 longitudinally-slidable in the said shaft and which projects through the front end 85 of the handle 18 where it is equipped with a suitable push button 79.

When the button and rod 78 are pushed inwardly the cam finger 76 engages the head 75 and through the instrumentalities above 90 described causes the return arm 65 to swing into the open space between the record and the carrier arms 37, where it engages the record and in the course of its movement forces the record back into the magazine 95 pocket from which it was withdrawn.

In use the operator grasps the handle 18 and through it effects a swinging of the arm 14 on its fulcrum 13. This movement brings the vertically disposed carrier arms 100 37 into register with the selected magazine pocket containing the record which it is desired to play. By now rotating the shaft 16 slightly through the medium of the handle the first rotation of the shaft serves 105 to bring the locking cam 23 into function to lock the parts in selected registering association.

Continued rotation of the shaft next causes the cam 24 to come into operation. 110 This serves to actuate the record discharge arm 28 which forces the selected record into the carrier arms 37.

At the time the operation was started the operator determined which side of the selected record he desired to play and the direction of rotation of the handle was in accordance with that choice. The next effect of the rotation of the shaft 16 is to cause the rack shifter cam to act to position the 115 selected rack for engaging the gear 47 to cause the necessary quarter turn of the carrier arms to bring the selected side of the record uppermost.

By this time the lost motion of the crank and link connections has been taken up and the crank 21 now effects a downward movement of the carrier to lower the record onto the turntable. As the carrier reaches the turntable the cam lugs 62 are engaged and 120 125 130

the carrier arms 37 are spread to free the record on the turntable.

Reverse rotation of the shaft 16 will return the parts to their normal position substantially in the order described except for the fact that the lifting of the carrier this time precedes the shifting of the rack and thus the previously shifted rack is left in position for returning the carrier to its normal position before being retracted by reverse action of the cam 20.

The actuator finger 76 and the cam head 75 will be in active association only when the carrier arms 37 are in their normal elevated and vertically disposed position and consequently only when the shaft 16 is in its normal position, and thus operation of the record return arm can be effected at the proper time only, or only at times when interference with the operation of other parts is impossible.

From the foregoing description, taken in connection with the accompanying drawings, it is thought that the novel details of construction, the manner of use and advantages of the invention will be readily apparent to those skilled in the art to which it relates.

What I claim is:

1. The combination with the phonograph turntable, of a record magazine located above and to one side of the turntable for impounding a plurality of records standing on edge, means to select a record from among the plurality and turn it into horizontal position, lower it and deposit it upon the turntable to be played, a cabinet for containing the aforesaid parts, and means operable by manual control from the outside of the cabinet for actuating said record selecting means.

2. The combination with the phonograph turntable, of a record magazine located above and to one side of the turntable for impounding a plurality of records standing on edge, means to select a record from among the plurality and turn it into horizontal position with a selected one of its two faces uppermost, lower it and deposit it upon the turntable to be played, a cabinet for containing the aforesaid parts, and means operable by manual control from the outside of the cabinet for actuating said record selecting means.

3. The combination with the phonograph turntable, of a record impounding magazine located above and to one side of the turntable and having a plurality of individual vertically disposed record receiving pockets, a record carrier and positioner having ways to receive a single record in a vertical plane and adapted to change the position of the record from vertical to horizontal, lower it and deposit it onto the said turntable to be played, and means to remove a record from

a magazine pocket and deposit it into the said carrier ways, a cabinet for the aforesaid structure, and means operable outside of the cabinet for effecting operation of said record removing and depositing means.

4. The combination with the phonograph turntable, of a record impounding magazine located above and to one side of the turntable and having a plurality of individual vertically disposed record receiving pockets, a record carrier and positioner having ways to receive a single record in a vertical plane and adapted to change the position of the record from vertical to horizontal, lower it and deposit it onto the said turntable to be played, means to move the carrier and positioner in a selected direction by changing its position to cause a selected side of the record to be positioned uppermost on the said turntable, and means to remove a record from a magazine pocket and deposit it into the said carrier ways, a cabinet for the aforesaid structure, and means operable outside of the cabinet for effecting operation of said record removing and depositing means.

5. The combination with the phonograph turntable, of a record impounding magazine located above and to one side of the turntable and having a plurality of individual vertically disposed record receiving pockets, a record carrier and positioner having ways to receive a single record in a vertical plane and adapted to change the position of the record from vertical to horizontal, lower it and deposit it onto the said turntable to be played, means to bring about relative movement between the magazine and the record carrier and positioner for the purpose of causing the carrier and positioner ways and a selected one of the magazine pockets to register, and means to remove a record from a magazine pocket and deposit it into the said carrier ways, a cabinet for the aforesaid structure, and means operable outside of the cabinet for effecting operation of said record removing and depositing means.

6. The combination with the phonograph turntable, of a record impounding magazine located above and to one side of the turntable and having a plurality of individual vertically disposed record receiving pockets, a record carrier and positioner having ways to receive a single record in a vertical plane and adapted to change the position of the record from vertical to horizontal, lower it and deposit it onto the said turntable to be played, means to bring about relative movement between the magazine and the record carrier and positioner for the purpose of causing the carrier and positioner ways and a selected one of the magazine pockets to register, means to remove a record from a magazine pocket and deposit it into the said carrier ways, and means to lock the said last named means at selected positions, a cabinet

for the aforesaid structure, and means operable outside of the cabinet for effecting operation of said record removing and depositing means.

an actuator finger extension, and a cam to engage the finger for the purpose of moving the arm.

11. In apparatus of the character described, a magazine having spaced individual record pockets, a record discharging arm movable in the space between two pockets and having an offset head to move in the plane of one of the pockets, said arm having an actuator finger extension, and a cam to engage the finger to project and retract the arm for the purpose described. 70 75

12. In apparatus of the character described, the combination with a phonograph turntable, of record carrying and positioning means comprising a pair of spaced arms to receive a record in vertical position, means to store up tension in the arms to cause them to grip the record with retaining friction, means to relieve the tension when the arms are at the normal vertical position, and means to change the position of the arms from the vertical to the horizontal and to lower them into associated relation with the turntable, a cabinet enclosing the aforesaid structure, and means operable from the outside of the cabinet for actuating said record carrying and positioning means.

13. In apparatus of the character described, the combination with a phonograph turntable, of record carrying and positioning means comprising a pair of spaced arms to receive a record in vertical position, means to store up tension in the arms to cause them to grip the record with retaining friction, means to change the position of the arms from the vertical to the horizontal and to lower them into associated relation with the turntable, and means to spread the arm when they are lowered to effect a depositing of the record onto the turntable, a cabinet enclosing the aforesaid structure, and means operable from the outside of the cabinet for actuating said record carrying and positioning means. 100 105 95

14. In apparatus of the character described, the combination with a phonograph turntable, of record carrying and positioning means comprising a pair of spaced arms to receive a record in vertical position, and means to change the position of the arms by movement thereof in a selected direction from the vertical to the horizontal and to lower them into associated relation with the turntable with a selected face of the record uppermost, a cabinet enclosing the aforesaid parts, means operable from the outside of the cabinet for effecting operation of said record carrying and positioning means.

15. In apparatus of the character described, the combination with a phonograph turntable, of record carrying and positioning means comprising a pair of spaced arms to receive a record in vertical position, means to change the position of the arms by movement thereof in a selected direction

from the vertical to the horizontal and to lower them into associated relation with the turntable with a selected face of the record uppermost, said last named means including a standard, a slide block vertically slideable on the standard, a shaft rotatably mounted in the block and carrying the said arms, a gear on the shaft, selectively positioned racks to engage the gear at one side or another to impart a quarter turn to the shaft as the block is lowered, means to lower the block, and means to store up tension in the arms to cause them to grip the record with retaining friction, and means to spread the arms when they are lowered to effect a depositing of the record onto the turntable.

16. In apparatus of the character described, the combination with a phonograph turntable, of record carrying and positioning means comprising a pair of spaced arms to receive a record in vertical position, means to change the position of the arms by movement thereof in a selected direction from the vertical to the horizontal and to lower them into associated relation with the turntable with a selected face of the record uppermost, said last named means including a standard, a slide block vertically slideable on the standard, a shaft rotatably mounted in the block and carrying the said arms, a gear on the shaft, selectively positioned racks to engage the gear at one side or another to impart a quarter turn to the shaft as the block is lowered, means to lower the block, and means to store up tension in the arms to cause them to grip the record with retaining friction.

17. In apparatus of the character described, the combination with a phonograph turntable, of record carrying and positioning means comprising a pair of spaced arms to receive a record in vertical position, means to change the position of the arms by movement thereof in a selected direction from the vertical to the horizontal and to lower them into associated relation with the turntable with a selected face of the record uppermost, said last named means including a standard, a slide block vertically slideable on the standard, a shaft rotatably mounted in the block and carrying the said arms, a gear on the shaft, selectively positioned racks to engage the gear at one side or another to impart a quarter turn to the shaft as the block is lowered, means to lower the block, means to store up tension in the arms to cause them to grip the record with retaining friction, and means to relieve the tension when the arms are at the normal vertical position.

18. In apparatus of the character described, the combination with a phonograph turntable, of record carrying and positioning means comprising a pair of spaced arms to receive a record in vertical position, means to change the position of the arms by movement thereof in a selected direction from the vertical to the horizontal and to lower them into associated relation with the turntable with a selected face of the record upper-

most, said last named means including a standard, a slide block vertically slideable on the standard, a shaft rotatably mounted in the block and carrying the said arms, a gear on the shaft, selectively positioned racks to engage the gear at one side or another to impart a quarter turn to the shaft as the block is lowered, means to lower the block, and means to store up tension in the arms to cause them to grip the record with retaining friction, and means to spread the arms when they are lowered to effect a depositing of the record onto the turntable.

19. In apparatus of the character described, the combination with a phonograph turntable, of record carrying and positioning means comprising a pair of spaced arms to receive a record in vertical position, means to change the position of the arms from the vertical to the horizontal and to lower them into associated relation with the turntable, and again restore them to their normal position, and means to remove the selected record from the arms and return it to the magazine, a cabinet enclosing the aforesaid parts, and means operable from the outside of the cabinet for effecting the action of the record carrying and positioning means.

20. In apparatus of the character described, the combination with a phonograph turntable, of record carrying and positioning means comprising a pair of spaced arms to receive a record in vertical position, means to change the position of the arms from the vertical to the horizontal and to lower them into associated relation with the turntable, and again restore them to their normal position, and means to remove the selected record from the arms and return it to the magazine pocket from which it was removed, a cabinet enclosing the aforesaid parts, and means operable from the outside of the cabinet for effecting the action of the record carrying and positioning means.

21. In apparatus of the character described, the combination with a phonograph turntable, of record carrying and positioning means comprising a pair of spaced arms to receive a record in vertical position, means to change the position of the arms from the vertical to the horizontal and to lower them into associated relation with the turntable and again restore them to their normal position, means to remove the selected record from the arms and return it to the magazine, said last named means including an oscillatable arm, rocker arm and crank connections to oscillate the arm, and a reciprocating rod having a cam finger to actuate the crank.

22. The combination with the phonograph turntable, of a record impounding magazine having a plurality of individual vertically

disposed record receiving pockets, a swing arm swingable in a horizontal plane about a vertical axis and carrying a standard, record carrying and positioning means supported on the standard and including arms to receive a single record in a vertical plane and adapted to change the position of the record from the vertical to the horizontal and deposit it onto the said turntable, and means carried by the swing arm to remove a record from a magazine pocket and deposit it into the said carrier and positioner arms, the said swing arm being swingable to position the arms in register with a selected one of the magazine pockets.

23. The combination with the phonograph turntable, of a record impounding magazine having a plurality of individual vertically disposed record receiving pockets, a swing arm swingable in a horizontal plane about a vertical axis and carrying a standard, record carrying and positioning means supported on the standard and including arms to receive a single record in a vertical plane and adapted to change the position of the record from the vertical to the horizontal and deposit it onto the said turntable, means carried by the swing arm to remove a record from a magazine pocket and deposit it into the said carrier and positioner arms, the said swing arm being swingable to position the arms in register with a selected one of the magazine pockets, and means to lock the swing arm at adjusted positions.

24. The combination with the phonograph turntable, of a record impounding magazine having a plurality of individual vertically disposed record receiving pockets, a swing arm swingable in a horizontal plane about a vertical axis and carrying a standard, the individual magazine pockets all being directed in converging lines intersecting the axis of rotation of the turntable, the vertical axis on which the swing arm moves being coincident with the said turntable axis of rotation, record carrying and positioning means supported on the standard and including arms to receive a single record in a vertical plane and adapted to change the position of the record from the vertical to the horizontal and deposit it onto the said turntable, and means carried by the swing arm to remove a record from a magazine pocket and deposit it into the said carrier and positioner arms, the said swing arm being swingable to position the arms in register with a selected one of the magazine pockets.

25. The combination with the phonograph turntable, of a record impounding magazine having a plurality of individual vertically disposed record receiving pockets, a swing arm swingable in a horizontal plane about a vertical axis and carrying a standard, a slide block vertically slidable on the stand-

ard, a shaft rotatably mounted in the block, a pair of spaced arms adapted normally to be disposed in a vertical plane and having ways to receive a record from a selected one of the magazine pockets, a gear on the shaft, selectively positioned racks to engage the gear at one side or another to impart a quarter turn to the shaft as the block is lowered, means to lower the block, means to move a record from a selected magazine pocket into the arm ways, and means to remove a record from the arm ways and return it to the said pocket.

26. The combination with the phonograph turntable, of a record impounding magazine having a plurality of individual vertically disposed record receiving pockets, a swing arm swingable in a horizontal plane about a vertical axis and carrying a standard, a slide block vertically slidable on the standard, a shaft rotatably mounted in the block, a pair of spaced arms adapted normally to be disposed in a vertical plane and having ways to receive a record from a selected one of the magazine pockets, a gear on the shaft, selectively positioned racks to engage the gear at one side or another to impart a quarter turn to the shaft as the block is lowered, means to lower the block, means to move a record from a selected magazine pocket into the arm ways, means to remove a record from the arm ways and return it to the said pocket, means to swing the swing arm to bring the spaced arm ways into register with a selected magazine pocket, and means to lock the swing arm in selected positions.

27. The combination with the phonograph turntable, of a record impounding magazine having a plurality of individual vertically disposed record receiving pockets, a swing arm swingable in a horizontal plane about a vertical axis and carrying a standard, a slide block vertically slidable on the standard, a shaft rotatably mounted in the block, a pair of spaced arms adapted normally to be disposed in a vertical plane and having ways to receive a record from a selected one of the magazine pockets, a gear on the shaft, selectively positioned racks to engage the gear at one side or another to impart a quarter turn to the shaft as the block is lowered, means to lower the block, means to move a record from a selected magazine pocket into the arm ways, means to remove a record from the arm ways and return it to the said pocket, means to swing the swing arm to bring the spaced arm ways into register with a selected magazine pocket, means to lock the swing arm in selected positions, and a single rotatable shaft and means actuated thereby for actuating the said locking means, for selectively shifting the racks and for lowering the said block.

BENJAMIN L. GATES.
